Frank Carlson
ATTORNEY.

UNITED STATES PATENT OFFICE.

PER LUDVIG LARSON, OF METUCHEN, NEW JERSEY.

DETACHABLE BED-SEAT.

1,274,901.

Specification of Letters Patent. Patented Aug. 6, 1918.

Application filed May 21, 1918. Serial No. 235,754.

To all whom it may concern:

Be it known that I, PER LUDVIG LARSON, a subject of King Gustavus V of Sweden, and residing at Sner End Triest, Metuchen, New Jersey, county of Middlesex, have invented certain new and useful Improvements in Detachable Bed-Seats, of which the following is a specification.

This invention relates to detached seats, and especially to that class wherein a seat may be attached to the end of a bedstead.

One advantage of my invention is to attach a seat to a bed and thereby make it unnecessary to sit in bed while dressing.

Another advantage is to provide a seat which may be easily attached or detached without altering the bed to which it may be fastened.

Another advantage is to provide a bed with an end seat which need not be removed but may be simply raised into an inconspicuous position.

Another advantage is to provide a bed with an end seat which in its raised position serves as footboard or footrest.

Another advantage is to provide a bed with an end seat which is very simple to construct and use, while being much cheaper than any chair. Further advantages and possibilities will become apparent as the specification proceeds.

Referring to the drawing Figure 1 is a side view of one end of a bed provided with an apparatus embodying my invention.

Fig. 2 is a similar view wherein my invention is being lowered into useful position.

Fig. 3 is a similar view with my invention in its proper useful position.

Fig. 4 is a perspective view of an apparatus embodying my invention, a part of board 2 being torn away to disclose the construction.

Throughout the views the same numerals refer to the same parts.

It not infrequently happens that in hospitals, cantonments and similar places where beds are arranged in long rows in considerable numbers, that space is at a premium and chairs or benches cannot be conveniently placed near the beds. Hence it has been customary to let the occupants of the beds sit in them while dressing. This is neither

convenient nor does it treat the beds right, as all the strain comes on one side and has a tendency to make that side sag.

As chairs are out of the question in most such places, especially in the cantonments and similar camps, I propose to attach a seat to the end of each bed, which is both simple and will extend out into the aisles between the rows of beds where there always is sufficient room.

My invention at its two parallel extremities is provided with integral hooks 3 and 5. In the straight portion of the frame is permanently secured a strip 16 to which a board 2 is fastened by means of hinges 4 and 14. The frame 6 is retained in shape by a rod 1 which has a further function as will presently develop. Two corners of board 2 have been cut out at 11 and 13 to fit the posts 12 of the bed 10, frame 6 being provided with an inner portion 7 to support board 2 in position.

To attach my invention to the bed, it is merely necessary to drop it into position on bracket 9 as seen in Fig. 1. In this position a hook 8, which is secured to frame 6 retains the seat in upright position, the whole apparatus resting on the brackets 9 beneath rod 1. In this position the seat is an admirable footboard, also cutting all direct drafts from the feet. If the top of frame 6 is now drawn outward and the mattress 15 raised a little, the frame will clear posts 12 and board 2 will open upward, the whole apparatus assuming the position of Fig. 2.

When frame 6 is drawn downward as far as it will go, hooks 3 and 5 engage the lower edges of the bed 10, the rod 1 resting on brackets 9, while board 2 drops into the frame and engages posts 12 by means of cuts 11 and 13. The seat is then locked in the position shown in Fig. 3 and cannot tip or be accidentally raised except by first raising board 2. Throughout these simple movements of the seat, it will be noted that rod 1 is a fulcrum, lying on the brackets which support the spring and is limited between posts 12 and frame 10.

It is obvious that I could construct frame 6 differently, omitting shoulder 7 and instead extending the ends of board 2 to engage the frame similarly as now. I reserve all rights to such changes and modifications.

as may be deemed commensurate with the scope of my invention.

Having thus fully described my invention, I claim:

5. 1. An end seat for beds including a **U** frame retained in shape by means of a rod secured to the limbs thereof and within the extremities of the same, hooks upon the inner opposite faces of said extremities, and
10 a hook adapted to engage the top of said bed secured to the portion of said **U** frame parallel with said rod.
  2. A folding seat including a **U** frame having a rod secured between the limbs of
15 said frame adapted to act as a fulcrum when raising or lowering said frame and a panel fitted within said frame.
  3. A folding seat including a **U** frame provided with oppositely situated inward
20 extensions terminating in opposite hooks arranged in line and adapted to engage the lower edges of a bed within the posts thereof and a panel adapted to set into the bowed portion of said frame.
  - 25 4. A detachable seat including a **U** frame provided on the extremities of both limbs with opposite hooks adapted to engage the frame of a bed, a fulcrum adapted to rest on said bed frame on each of said limbs
- within said hooks, a panel or board adapted to set into said **U** frame and means to support said panel in position. 30
5. A detachable seat including a **U** frame provided with a tie rod between the limbs thereof and having the middle portion generally parallel with said rod; a board hinged to said middle portion and means to support said board when set into said frame. 35
  6. A detachable bed seat including a horse shoe frame adapted to straddle a bed, a tie-rod secured between the limbs of said frame within the extremities of said limbs adapted to rest directly upon said bed, a hook mounted upon said frame engaging one end of said bed to retain said frame in an upright position, and a board hinged to the portion of said frame generally parallel with said rod, and inward extensions upon said frame to support said board. 40

Signed at 132 Nassau street, in the 50
borough of Manhattan, county of New York,
city and State of New York, this 18th day
of May, 1918.

PER LUDVIG LARSON.
